UNITED STATES PATENT OFFICE.

JOHN WYCKOFF METTLER, OF EAST MILLSTONE, NEW JERSEY, AND HAMILTON LEE DAVIS, OF MARTINSBURG, WEST VIRGINIA, ASSIGNORS TO THE INTERWOVEN MILLS, INC., OF NEW BRUNSWICK, NEW JERSEY, A CORPORATION OF NEW JERSEY.

CIRCULAR-KNITTING MACHINE.

Application filed April 24, 1925. Serial No. 25,478.

Our invention consists in the novel features hereinafter described, reference being had to the accompanying drawings, which illustrate one embodiment of the same, selected by us for purposes of illustration, and the said invention is fully disclosed in the following description and claims.

The object of our invention is to provide a knitting machine for knitting a seamless stocking of the split foot type in which the leg, heel and a plurality of courses of the sole portion, immediately forward of the heel are all knit of dyed yarn, the remaining portion of the sole of the foot portion, and the toe being knit with undyed yarn. In the manufacture of split foot stockings heretofore, provided with undyed sole and toe portions, the entire sole portion was usually knitted with undyed yarn and when the stocking was worn with low shoes, the upper corners of the undyed sole adjacent to the heel, on opposite sides of the foot, showed above the edge of the shoe and produced an unsightly effect, which is very objectionable, and which interferes with the sale of this kind of hosiery. We have discovered that when a stocking is stretched upon the foot, the wales of the sole portion immediately adjacent to the heel, on each side of the foot are drawn into such a position that they extend forwardly and at a very sharp angle downwardly from the upper forward corner of the heel at each side of the stocking. The machine of this application is constructed to knit a stocking provided with a plurality of partial courses of dyed yarn in the sole portion thereof, immediately forward of the heel before beginning to knit the sole portion with an undyed yarn, thereby carrying the upper and rear corners of the undyed sole considerably forward and considerably downward from the upper forward corners of the heel pocket so that the undyed sole portion will not be visible when the stocking is worn with low shoes or slippers. Any desired number of such courses of dyed thread can be made in the sole so as to carry the upper rear corners of the undyed sole as far downwardly and forwardly as may be desired to accomplish the result mentioned. Our present invention consists in an improved knitting machine for the com-

mercial manufacture of this split foot stocking.

In carrying out our present invention, we prefer to employ the well known Banner machine, such as illustrated in the United States Letters Patent to Hemphill, No. 933,443, dated September 7, 1909, adapted for the manufacture of split foot stockings, and to make certain alterations and additions to this machine for the purpose of carrying out our invention, and producing the new stocking above described.

In the accompanying drawings,

Fig. 1 is a partial front view of a knitting machine embodying our invention.

Fig. 2 is a top plan view of the machine with the thread supporting devices removed, and illustrating the general arrangement of the thread guides.

Fig. 3 is a partial side elevation of the machine.

Fig. 4 is a detail view of our improved mechanism for imparting a partial movement to the pattern wheel, as hereinafter described.

Figs. 5, 6, 7, and 8, are details of parts of the mechanism.

Fig. 9 is a view of the stocking produced by our improved machine.

As the construction of the Banner machine is so well known, we will only describe the changes which we have made therein for the purpose of carrying out our present invention. The machine is preferably provided with four main thread guides, as indicated in Fig. 2, at 1, 2, 3 and 4, located at one side of the circular series of needles. The circular series of needles includes a series of long butt needles, which knit the front half of the leg and top of the foot of the stocking, and a series of short butt needles which knit the back of the leg, heel, the sole of the foot and toe, in the usual manner. An auxiliary thread guide, indicated at 5 in the same figure, is also provided and located diametrically opposite to the first mentioned thread guides, as is customary in these machines.

In the operation of the machine for the production of our new stocking, the knitting of the leg and heel portion proceeds in substantially the same manner as heretofore, and involves no changes in the Banner ma-

chine. In the ordinary operation of the machine after the final widening courses of the heel are knit, the foot has been knit as a split foot fabric, by reciprocating knitting on each half of the needles, the needles knitting the top of the foot being supplied with dyed yarn such as is used in the leg portion, and the needles knitting the sole portion of the foot being supplied with undyed yarn. This change is accomplished automatically in the Banner split foot machine by imparting to the coarse ratchet toothed cam wheel, indicated at 6, what may be termed a full forward pull, equivalent to the distance between two adjacent teeth, which is imparted to it by the pawl, indicated at 7 in Fig. 7, which is lowered into position to engage the wheel, 6, at such time, by the operation of the pawl supporter, 8, under the action of a double feed lug, 9, on the pattern chain, 10, which has the effect on the commencement of the split foot, of restoring the long butt needles knitting the top of the foot, to knitting position, by depressing the draw-down cam, indicated at 11, in Fig. 1, and at the same time throwing out of operation the thread guide which has supplied the dyed thread for the heel courses, and bringing into operation a thread guide supplying an undyed thread to the short butt needles, the long butt needles being supplied with dyed thread from the auxiliary thread guide. In carrying out our invention, it is necessary to change the operation of the machine at this point, by imparting only a half pull to the cam wheel, 6, for the purpose of permitting the next half courses of the sole to be knit with the same dyed thread which has been supplied by the proper thread guide of the main guides, to the short butt needles during the knitting of the heel, and to provide other means brought into operation at the proper time, to impart the other half pull to the cam wheel, 6, after the desired number of sole courses have been knit with dyed thread, to complete the change which is made after the completion of the normal heel.

In carrying out our invention, we therefore make the following changes in the Banner machine. The draw-down cam, 11, is lengthened to the right, as indicated at 11^a, in Fig. 1, to insure the drawing down of the long butt needles, so that on the first half pull imparted to the pattern mechanism, after the heel is completed, the needles held out of operation during the knitting of the heel, will be drawn down in the same manner as they would be by the full pull of the ratchet wheel in the operation of an ordinary split foot Banner machine. At the proper point in the ratchet wheel, 6, a tooth is eliminated, as indicated at 13, and an extra tooth, or notch, indicated at 14, is provided between the tooth that is eliminated and the next tooth preceding, indicated at 15, so that,

when the pawl, 7, is drawn forwardly after the completion of the heel, the usual distance, it will not engage the wheel, 6, at the point, 13, but will slide forward until it strikes the extra tooth, 14, and will thus move the wheel only half of the usual distance, or in other words, the distance between the dotted lines *x* and *y* in Fig. 7. The wheel, 6, is moved the additional distance indicated between the dotted lines *x* and *z*, in Fig. 7, or in other words, the other half pull, after the completion of the desired number of partial courses of the sole with the dyed thread, by other mechanism hereinafter described.

It is also necessary to change the clutch operating cams, 16 and 17 (Fig. 1), in order to have the clutch operate in time with the new notch, 14, above referred to, and to this end, the cam, 16, is shortened the required distance, and the cam, 17, lengthened, as indicated at 17^a, to insure the proper operation of the clutch after the completion of the heel.

In order to provide the second half pull on the wheel, 6, covering the distance represented between the dotted lines *x* and *y*, we have provided the stop motion wheel, 18, on its periphery, with a lug, indicated at 19, adapted to be engaged by a pawl, 20, pivoted at 21, to a horizontal reciprocating bar, 22, or slide, mounted in guides, 23, secured to the side frame of the machine and caused to reciprocate at the proper time, by connecting it with a suitable part of the machine for that purpose. In this instance we have provided, the heel and toe evener dog, 24, with an extension, indicated at 25, provided with a plurality of apertures, 26, for the purpose of pivotally connecting thereto one end of a connecting rod, 27, the other end of which is connected at 28, with the bar, 22. The several apertures, 26, are provided for the purpose of securing just the desired amount of throw for the slide, 22, and its connected pawl, 20. Thus the pawl, 20, is drawn downwardly by a spring, 29, secured to a bracket, 30, carried by the slide, 22, for the purpose of preventing it from jumping while the machine was in operation, and we provide means for holding the pawl, 20, out of operation with the stop motion wheel, 18, until the time when it is desired that the pawl shall operate in connection with the stud, 19. For this purpose we provide the rear end of the pawl supporter, 8, with a lateral arm, indicated at 31 (see Fig. 5) carrying an adjustable stop, 32, secured thereto by means of a set screw, 33, and adjustable in a rotary direction on the rod, 31, so as to insure its holding the pawl, 20, in such a position that it will not prematurely engage the stud, 19. When further, the pawl supporter, 8, is operated by the engagement of a special link stud on the pattern chain, provided for the purpose of dropping the

pawl at a halfway point, with the V-shaped projection, 8^a, on the pawl supporter, 8, the forward end of the pawl supporter will be raised and the rear end lowered, carrying with it the rod, 31, and adjustable stop, 32, and permitting the pawl, 20, to engage the stud, 19, and impart the second half of the pull, represented as the distance between the dotted lines α and β in Fig. 7, to the ratchet wheel, 6, which brings all the parts of the machine into the same relative position which they would occupy had the ratchet wheel, 6, been given the normal or full pull at the conclusion of the knitting of the heel, and thus permitting the knitting of the partial or half courses of the sole immediately adjacent to the heel with the same thread carrier with which the heel itself was knit, and which carries a dyed thread. The other parts of the machine not specifically referred to, it will be understood are of the usual construction in the Hemphill split foot knitter.

We will now describe briefly the manner in which the machine is operated for the production of our improved split foot stocking. Thread guide #1, is supplied with a dyed thread of which it is desired to knit the main body of the leg of the stocking. Thread guide #2, is supplied with a heavier dyed thread, suitable for use in knitting the high-splice heel and dyed portion of the sole. Thread guide #3 is supplied with an undyed thread of character suitable for the knitting of the sole of the stocking, forward of the section immediately in front of the heel, which, as before stated, is knit with the dyed thread. Thread guide #4, is provided with an undyed thread or threads, of a character suitable for the knitting of the toe band and toe pocket, and preferably somewhat heavier than the thread delivered by the thread guide, 3. The auxiliary thread guide, 5, is supplied with the same character of dyed thread that is carried by the thread guide, 1, for knitting the top portion of the foot.

Assuming that the stocking is to be knit from the top of the leg portion to the toe, and that in knitting a man's sock, the usual ribbed top has been transferred to the needles of the machine, the leg portion is knit by circular knitting on all of the needles using thread guide #1, and feeding dyed yarn to all of the needles. The leg may be so knit to the heel pocket if desired, but we prefer to reinforce the high spliced portion above the heel, and therefore circular knitting is stopped at the top of the high spliced portion, and reciprocating knitting is effected on all of the needles, feeding the needles which knit the rear half or high spliced portion of the stocking by means of thread guide, 2, carrying the heavier dyed thread, and bringing into action the auxiliary thread

guide, 5, carrying the same kind of thread as guide 1 to knit the front portion of the leg, the front and rear sections of the leg portion so knit being united at the sides by sutures, in the usual manner. As soon as the heel is reached, the long butt needles which knit the front portion of the stocking are raised to inoperative position, and hold their stitches. The auxiliary thread is thrown out of operation and the heel is knit by reciprocating knitting and narrowing and widening in the usual manner with the heavier dyed thread carried by thread guide, 2, to the end of the heel section. At this point reciprocating knitting on all of the needles is resumed by reason of the half pull imparted to the wheel, 6, throwing in the auxiliary thread guide 5 and leaving the thread guide, 2, in operation, thereby knitting a desired number of courses of split sole work with the finer dyed yarn from thread guide 5 in the partial courses of the top of the foot with the heavier dyed yarn delivered by guide, 2, and previously used in the heel, forming the sole portion adjacent to the heel as previously described. After any desired number of such courses have been made, which may be determined by the placing of the link in the pattern chain carrying the stud which trips the pawl supporter, 8, the pawl supporter will be actuated, thereby permitting the pawl, 20, to drop into operative relation with the stud, 19, on the stop motion wheel, 18, so that the forward movement of the pawl, 20, will carry the ratchet wheel, 6, the additional half pull necessary to bring the parts into the position which they would normally occupy had the entire pull been given to the ratchet wheel, 6, after the heel courses are completed. This throws out of operation, thread guide, 2, and throws in thread guide, 3, carrying the undyed sole thread, the auxiliary thread guide, 5, remaining in operation and knitting of the split foot proceeds by reciprocating knitting on all the needles with the thread supplied by guides, 3 and 5, respectively, thus forming a split foot having an undyed sole. This split foot knitting continues to the point occupied by the toe band, when the machine, under the operation of the usual pattern mechanism, throws the thread guides 3 and 5, out of operation, and puts into operative position, thread guide, 4, carrying the heavier undyed thread, and the machine then operates by circular knitting on all of the needles to form a plurality of courses of what is known as the toe band, of undyed heavier thread, in both the sole and top of the foot. As soon as the desired number of circular courses have been formed, the circular knitting is discontinued, and the toe pocket is knit with the thread guide, 4, carrying the undyed heavier thread, by reciprocating knitting and narrowing and

widening, with the additional partial courses known as the looper's edge. This completes the knitting of the stocking, which is completed by looping the last course of the toe pocket, with the corresponding partial course of the toe band, in the usual manner, by the use of a looper.

In Fig. 9 we have shown a diagrammatic view of the stocking knit by our improved machine, in which, 101, represents the leg of the stocking, which in this instance is a man's half hose, provided with the usual ribbed top, 102. 103 represents the high-spliced portion above the heel; 105, the heel pocket, and 106 represents the partial courses in the sole immediately forward of the heel, which are formed of dyed thread, as are the leg, heel and top of the foot. 107 represents the portion of the sole forward of the courses, 106, and formed of undyed thread, 108 represents the toe band, and 109 represents the toe, both of which are formed of undyed thread.

What we claim and desire to secure by Letters Patent is:—

1. In a split foot seamless stocking knitter of the kind described, in combination with the pattern mechanism thereof, for controlling the production of circular knitting, split work knitting, and reciprocating work on a section of the needles with narrowing and widening, including a ratchet wheel, and pawl mechanism therefor, means called into operation after the completion of the heel of the stocking, for operating said pawl mechanism to impart a partial movement to said ratchet wheel, to effect the resumption of split work knitting while continuing in operation the thread guide employed for supplying thread for the heel, and separate independent pawl mechanism, a rotary part operatively connected with said ratchet wheel and provided with a projection in the path of said independent pawl mechanism, and means called into operation after the formation of a predetermined number of courses of the foot adjacent to the heel for actuating said independent pawl mechanism, to effect a further rotary movement of said ratchet wheel, and throw out of operation the said thread guide, and throw into operation a separate thread guide for supplying the needles knitting the sole portions of the remaining courses of the foot.
2. In a split foot seamless stocking knitter of the kind described, in combination, pattern mechanism including a ratchet wheel, provided at one point with a special tooth spaced at substantially half the normal distance between teeth from the preceding tooth and one and a half times the normal distance between teeth from the succeeding tooth, a pawl engaging said special tooth to produce a half pull of the ratchet wheel at one point in its revolution, a stop motion wheel oper-

tively connected with said ratchet wheel, and provided with a peripheral lug, a pawl for engaging said lug to impart a second half pull to said ratchet wheel, means for holding said last mentioned pawl out of operation until a plurality of foot courses following the completion of the heel pocket are knit, and means for dropping said pawl into position to engage said lug, and for actuating said pawl.

3. In a split foot seamless stocking knitter of the kind described, in combination, pattern mechanism, including a ratchet wheel, provided at one point with a special tooth spaced at substantially half the normal distance between teeth from the succeeding tooth, a pawl engaging said special tooth, to produce a half pull of the ratchet wheel at one point in its revolution, a stop motion wheel operatively connected with said ratchet wheel, and provided with a peripheral lug, a pawl for engaging said lug to impart a second half pull to said ratchet wheel, means for holding said last mentioned pawl out of operation until a plurality of foot courses following the completion of the heel pocket are knit, means for lowering said pawl into operative relation with the said lug, a reciprocating bar to which said pawl is pivoted, and a link connecting said reciprocating bar to the heel and toe evener dog operating shaft for reciprocating said bar.

4. In a split foot seamless stocking knitter of the kind described, in combination, pattern mechanism, including a ratchet wheel provided at one point with a special tooth spaced at substantially half the normal distance between teeth from the preceding tooth and one and a half times the normal distance between teeth, from the succeeding tooth, a pawl engaging said special tooth to produce a half pull of the ratchet wheel at one point in its revolution, a stop motion wheel operatively connected with said ratchet wheel, and provided with a peripheral lug, a pawl for engaging said lug to impart a second half pull to said ratchet wheel, a pivoted pawl supporter for holding the first mentioned pawl out of operative position, a pattern chain provided with studs for operating said pawl supporter, a part connected with said pawl supporter for normally engaging said second mentioned pawl and holding it out of operative relation with the said lug, and means for operating said last mentioned pawl, and a special lug on the pattern chain for operating said pawl supporter.

5. In a split foot seamless stocking knitter of the kind described, in combination, pattern mechanism, including a ratchet wheel, provided at one point with a special tooth spaced at substantially half the normal distance between teeth from the preceding tooth, and one and a half times the normal distance

between teeth from the succeeding tooth, a pawl engaging said special tooth to produce a half pull of the ratchet wheel at one point in its revolution, a stop motion wheel 5 operatively connected with said ratchet wheel, and provided with a peripheral lug, a pawl for engaging said lug to impart a second half pull to said ratchet wheel, a pivoted pawl supported for holding the first mentioned pawl out of operative position, a pattern chain provided with studs for operating said pawl supporter, a part connected with said pawl supporter for normally engaging said second mentioned pawl and holding it out of 10 operative relation with the said lug, a reciprocating bar to which said last mentioned pawl is pivoted, an arm connected with the shaft of the heel and toe evener dog, and a link connecting said arm and said reciprocating bar, and a special lug on the pattern chain for operating the pawl supporter to lower said last mentioned pawl into operative 15 relation to the said peripheral lug.

6. In a split foot seamless stocking knitter 20 of the kind described, in combination, pattern mechanism, including a ratchet wheel, provided at one point with a special tooth spaced at substantially half the normal dis-

tance between teeth, from the preceding tooth, and one and a half times the normal 30 distance between teeth from the succeeding tooth, a pawl engaging said special tooth to produce a half pull of the ratchet wheel at one point in its revolution, a stop motion wheel operatively connected with said ratchet 35 wheel, and provided with a peripheral lug, a pawl for engaging said lug to impart a second half pull to said ratchet wheel, means for holding said last mentioned pawl out of operation until a plurality of foot courses 40 following the completion of the heel pocket are knit, means for lowering said pawl into operative relation with the said peripheral lug, means for operating said pawl, clutch operating cams operating in timed relation 45 with said special tooth, on said ratchet wheel, and a draw-down cam for the needles held out of operation during the knitting of the heel pocket, provided with a laterally extended portion to insure the drawing down 50 of said needles after the said first half pull on said ratchet wheel.

In testimony whereof we affix our signatures.

JOHN WYCKOFF METTLER.
HAMILTON LEE DAVIS.
